UNITED STATES PATENT OFFICE.

JUDSON ROGERS DE NOYELLES, OF DETROIT, MICHIGAN.

TRACKER MECHANISM FOR PLAYER-PIANOS.

1,215,005.

Specification of Letters Patent.

Patented Feb. 6, 1917.

Application filed March 2, 1916. Serial No. 81,581.

To all whom it may concern:

Be it known that I, JUDSON R. DE NOYELLES, a citizen of the United States, residing at Detroit, in the county of Wayne and State of Michigan, have invented certain new and useful Improvements in Tracker Mechanism for Player-Pianos, of which the following is a specification, reference being had to the accompanying drawings.

10 This invention relates to player pianos and particularly to the tracker mechanism therefor.

15 The general object of my invention is the provision of a very simple tracker mechanism which will operate to positively shift the upper spool supporting the note sheet roll either in a direction toward the right or toward the left to compensate for any irregular unwinding of the note sheet from 20 the supporting roll.

25 A further object of the invention is to provide a construction of this kind wherein the parts are so formed that they will not bind and still another object is to provide a mechanism of the character described which is particularly applicable to what are known as foot players.

Other objects will appear in the course of the following description.

30 The invention is illustrated in the accompanying drawings, wherein—

Figure 1 is a front elevation, partly in section, of the wind chest, roll supporting and roll shifting mechanism of a player 35 piano showing my improvements applied thereto;

Fig. 2 is a fragmentary section through the end of one of the rolls through the adjacent supporting frame, and showing the 40 head 14 in elevation;

Fig. 3 is a fragmentary vertical section through the members 26 and 28 to show the hinged connection of these members;

Fig. 4 is a fragmentary elevation of the 45 lower portion of one of the bellows and of the hinge connecting it to the tracker rod, the tracker rod being shown in section;

Fig. 5 is a vertical section through the tracker bar, the section being taken so as 50 to intersect the bleed-openings 18 and 19;

Fig. 6 is a vertical longitudinal section of one of the valve boxes, showing the valves in elevation; and

Fig. 7 is a diagrammatic view illustrating the manner in which the valves operate. 55

Referring to these drawings, 10 designates the vacuum chest or wind chest of a player piano of the ordinary type, and 11 designates the frame supporting the take-up spool 12 and the roll spindles 13 and 14 which support the music roll 15. These shaft sections or spindles 13 and 14 have transverse movement with relation to the frames 11 in the usual manner so that the music roll may be shifted either to the left or to the right. 60 The note sheet 16 passes over the usual tracker bar 17 which is provided at its opposite ends with the primary ports or ducts 18 and 18^a and the secondary ports 19 and 19^a. The primary ports 18 and 18^a are disposed below the ports 19 and 19^a and inward of these ports, and the distance between the ports 19 and 19^a and therefore of course the distance between the ports 18 and 18^a is somewhat less than the width of the note 65 sheet 16 so that all of the ports are normally closed when the note sheet is tracking properly. As will be seen from Fig. 4, the secondary ports or openings 19 and 19^a are disposed on a higher level than the ports 18 and 18^a and are always covered by the note sheet except when the note sheet shifts to one side when air may pass through these ports, thus, causing the operation of the valves as will be later stated. Thus so long 70 as the note sheet is traveling properly it will cover the primary ports 18 and 18^a, but should the note sheet move far enough to the left it will uncover the primary port 18^a, and of course a sufficient shifting of the 75 note sheet to the right will uncover the port 18. The valve mechanism to which the ports 18, 18^a, and 19, 19^a, are connected will 80 be later stated.

For the purpose of shifting the spindles 95 13 and 14 to the right or to the left, as the case may be, I provide a tracker rod 20 which extends across the top of the frame 11 and has one end downwardly bent as at 21. The lower end of this downwardly bent portion 21 is formed with a socket 22 within which is engaged the spherical end 23 of the spindle 13, the connection between the spindle 13 and the enlarged lower end of the downward extension 21 of the tracker bar 100 forming a ball and socket joint. At its op-

posite end the tracker rod 20 is downwardly bent as at 25, and mounted thereon is a block 26 which might be made of wood, fiber or any other suitable material of like 5 nature, this being formed with a socket 27 extending parallel to the tracker rod 20. Pivoted to this block 26 is a block 28 which is also formed of wood or composition and which has an upwardly extending tongue 29 10 which extends into the socket or recess 27 and is pivoted to the block 26 by means of a pivot pin 30. A stop 31 is attached to the block 26 and extends down opposite the inner end of the block 28 and on the opposite 15 side of the block 26 there is attached a spring 32 which bears against the adjacent face of the block 28 and urges said block against the stop but yields to permit the block 28 to shift away from the stop 31. 20 The block 28 carries a downwardly extending arm 33 which at its lower end is formed with a socket 34 adapted to operatively engage with the spherical extremity 35 of the spindle 14.

25 Supported upon the frame 11 is a block 36 formed with a transversely extending opening 37 or passage through which the tracker rod 20 loosely passes, and mounted upon this block are the oppositely disposed bellows or 30 pneumatics 38 and 38^a. The free sides of the bellows are each connected to the tracker rod 20 each by means of a clamping hinge comprising a hinge member 39 attached to the lower margin of the free side of the 35 bellows and a hinge member 40 which is recessed to engage with a tongue projecting from the hinge member 39 and which is pivoted thereto by a pivot 41. These hinge members are made of hard fiber or like material, and members 39 are each provided 40 with the opening 42 through which the tracker rod passes, and a set screw 43 holds the hinge member in engagement with the tracker rod but permits the tracker rod to 45 be adjusted through the hinge member. As will be seen from Fig. 1, there are two of these hinges composed of the members 39 and 40 for each pair of bellows. Now it will be obvious that if the bellows 38 50 lapses and the bellows 38^a is distended, the tracker rod will be shifted to the left while it will be shifted to the right if the bellows 38^a is contracted and the bellows 38 distended.

55 Mounted upon the upper cross bar of the frame 11 are the tracker rod guides 44 and 45, the guide 44 extending outward and being slotted for engagement with the downwardly extending portion 21 of the tracker 60 rod while the guide 45 extends upward and is attached to the opposite end of the frame 11 and is slit for the passage of the adjacent portion of the tracker rod. Preferably, the tracker rod is formed in three sections, as 65 illustrated in section in Fig. 1, these sections

being adjustable toward or from each other and the ends of the sections entering the sleeves 73. Set screws 74 engage the sections of the tracker rod and hold them in adjusted relation.

The bellows 38 and 38^a are connected each to the tracker rod by the fiber hinges 30-40, the hinges allowing the rod to move more freely and to be less likely to bind than if the bellows were otherwise connected thereto. 75 The hinge section 40 will always remain in a vertical position, or at right angles to the tracker rod 20, and inasmuch as the tongue of the hinge member 39 is slotted for the passage of the pin 41 it will be obvious that sufficient play will be permitted to allow the proper movement of the bellows without cramping or binding the hinge members upon each other or upon the rod 20.

The parts 26, 28, 31 and 32 are for the purpose of permitting the spindle 14 to be shifted laterally to the left for the insertion of the music roll between the spindles. The spring 32, however, forces the member 28 normally against the stop 31 as soon as the music roll has been inserted so as to keep the roll in its proper position for tracking. Inasmuch as the spindles 13 and 14 are engaged with the extremities of the tracker rod 20 by ball and socket joints, it is obvious that there will be no binding action. The block which supports the bellows 38 and 38^a is formed with two separate ducts 46 and 47, the duct 46 being connected to the bellows 38 while the duct 47 is connected to the bellows 38^a. These ducts in turn are connected to tubes 48 and 49 which extend to the valve boxes 50 and 50^a, respectively. These valve boxes are alike, and within the valve boxes are disposed slow working valves 105 which control the bellows 38 and 38^a. Each of the valve boxes contains a primary and a secondary valve, and each valve box is connected to one of the primary ducts and the corresponding secondary ducts. 110

Each valve box, as shown in Fig. 6, is formed to provide a primary chamber 51 and a valve chamber 52 within which is disposed a primary valve 53. This primary valve has a stem 54 which extends down 115 through a relatively large opening connecting the primary chamber with the valve chamber, and in its turn is operatively engaged by a diaphragm 55 which separates the chamber 51 from a chamber 56, this chamber 56 in turn being connected by a duct 57 to the primary tube 58 or 58^a, as the case may be, leading to one of the primary ports 18 or 18^a, as the case may be. Between the duct 57 and the primary chamber there is a small bleed-hole 59. Each valve casing 50 or 50^a is also provided with a secondary chamber 60 connected by a relatively large opening to a secondary valve chamber 62 within which is located a secondary valve 120 125 130

63. From the top of the valve chamber 62 extends a vent pipe 64. The valve 63 has a stem 65 which extends down through the chamber 60 and at its lower end is operatively connected to a diaphragm 66 which separates the secondary chamber 60 from a chamber 67 connected by a duct 68 to a tube 69 or 69^a, as the case may be, which leads to one of the secondary bleed-openings or ducts 19 or 19^a, as the case may be. Each chamber 52 is connected to chamber 60 by a passage 61.

The chamber 60 is connected to the duct 68 by means of a relatively small bleed-opening 70. The chamber 51 of each valve casing is connected by a pipe 71 to the vacuum chamber or wind chest 10 so that the chamber 51 is normally exhausted. The secondary chamber 60 is connected by means of a duct or pipe 48 or 49 to the corresponding bellows 38 or 38^a, the valve chamber 60 being connected to the bellows 38 by pipe 49 and duct 47, the valve chamber 60 being connected to the bellows 38^a, through the ducts 49 and 47, respectively.

The operation of this invention is as follows: It is to be understood that the primary chambers 51 of both of the valves are connected to the wind chest 10 from which the air has been exhausted by the usual pedal-operated bellows. When the music sheet 16 is tracking properly, the primary ducts 18 and 18^a are closed. As before remarked, the chambers 51 of both valves are normally exhausted, as are the chambers 56 of both valves. Therefore, both of the valves 53 are down on their seats. The chambers 60 and 67 of both of the valves are normally filled with air as are the bellows 38 and 38^a. Now, we will assume that the note sheet shifts from its normal position toward the right in Fig. 1, thus inclosing the ports 18 and 19. Then, as shown diagrammatically in Fig. 7, the air will rush in through the opening 18 to the chamber 56 of the corresponding valve casing. This will cause the valve 53 to lift, opening communication between the chambers 51 and 60 which is of course in communication with the bellows 38. Air is thus exhausted from the chamber 60 and from the bellows 38 and the bellows 38^a collapses. The bellows 38^a has the same air pressure inside as outside and therefore moves freely.

The deflation of the bellows 38 causes the roll 15 to move to the left and the music sheet again closes duct 58, and the valve 53 drops, cutting off communication between the chamber 51 and the chamber 60. Now, when the valve 53 rose under the action of air entering through the port 18, it exhausted the air from the chamber 60 and unbalanced the valve 63 so that the pressure behind the diaphragm 66 causes this valve 63 to slowly rise and close against the air vent

64. As the valve 63 rises, and while the valve is in its intermediate position, air will pass downward through the opening 64 into the chamber 60, but this amount of air will be relatively slight in comparison with the amount being exhausted through the passage 61 so that the exhaustion will take place faster than air can be supplied to the chamber 60. The opening of communication between the port 64 and the chamber 60 will cause the valve 63 to rise very slowly. Eventually the valve 63 will close against the port 64 and then the chamber 60 will be exhausted entirely. When the music sheet is shifted again to the left by the action of the bellows 38, the music sheet will close the ports 18 and 19. The music sheet will first close the port 18, thus cutting off communication between the chamber 56. The air in the chamber 56 will be exhausted through the bleed-hole 59, and pressure being equalized, valve 53 will drop, cutting off communication between the chamber 51 and chamber 60. The pressure in chamber 60 will then become equalized with the pressure in the chamber 67 and the valve 63 will drop, allowing air to pass into the chamber 60 through the port 64 and to pass into the bellows. When the secondary valve closes it closes very slowly as the air is dead. This is particularly essential because if the shifting bellows 38 or 38^a worked quickly it would not give the music sheet a chance to shift and would tear the sheet.

The advantages of my invention are as follows: The mechanism is very simple and at the same time a positive shifting of the music roll 15 is secured in both directions and not merely in one direction as is often done. Furthermore, the tracker rod 20 moves parallel to the roll supporting spindles 13 and 14 and parallel to the roll, and therefore there will be no binding. Any binding of the spindles 13 and 14, however, is further prevented by the ball and socket joint between the spindle 13 and the end of the arm 21 and between the spindle 14 and the socket carried upon the arm 25 of the tracker rod. At the same time the construction illustrated permits the roll to be easily inserted into engagement with the spindles 13 and 14 and as readily removed. It will be obvious that the tracking mechanism described operates positively to shift the roll either to the right or to the left and that the operation is very free. Furthermore, it will be obvious that the mechanism can be readily applied to player pianos as at present constructed without any alteration in the usual mechanism thereof other than as above described. Slow operating valves are particularly necessary, as above pointed out, in order to prevent the note sheet from being torn while being shifted back to its normal position.

In the drawings the mechanism for driving the rolls, re-winding and the tempo mechanism has of course not been illustrated as it is well known and may be of any ordinary or usual type.

Having described the invention, what I claim is:

1. In a tracker mechanism for player pianos, the combination with oppositely disposed longitudinally movable roll supporting spindles, of a tracker rod movable parallel to the axes of the spindles, one end of the tracker rod being extended downward to a point opposite one of said spindles and being there provided with a socket, the corresponding head being formed with a ball rotatable in said socket, the other end of the tracker rod being downwardly extended and provided with a terminal member, a member hingedly connected to the terminal member for movement in the plane of movement of the corresponding head and tracker rod, said hinged member having a socket, the corresponding spindle being formed with a ball engaging with the socket, said terminal member carrying a stop engaging with the hinged member to prevent its movement toward the oppositely disposed head, a spring mounted upon the terminal member and engaging with the hinged member to yieldingly hold the hinged member from movement away from the stop, and means for shifting the tracker rod.

2. In a tracker mechanism for player pianos, a supporting frame, oppositely disposed aligned music roll supporting spindles rotatably mounted in the frame, and a tracker rod extending across the top of the frame and having downwardly extending ends having rotative engagement with the spindles, a pair of pneumatics mounted above the tracker rod and having arms movable by the action of the pneumatics, and members clamped upon the tracker rod and having pivotal connection to said arms.

3. In a tracker mechanism for player pianos, a longitudinally movable rotatably supported roll supporting spindle, a tracker rod bent at one end to extend at right angles to the spindle, a member pivotally connected to the angularly bent end of the tracker rod

for engagement with the extremity of the roll supporting spindle, a stop limiting the movement of the member in one direction, and a spring urging said member against the stop.

4. In a tracker mechanism for player pianos, a rotatably supported music roll supporting spindle longitudinally shiftable along its axis, and a tracker rod having at its extremity a socket, the adjacent extremity of the supporting spindle being provided with a ball fitting in said socket, and means for longitudinally shifting the tracker rod.

5. In a tracker mechanism for player pianos, a supporting frame, oppositely disposed aligned roll supporting spindles rotatably mounted in the frame for longitudinal movement, a tracker rod extending across the top of the frame and slidably supported thereon and having downwardly extending ends having rotative engagement with the spindles, the tracker rod and spindles having unitary longitudinal movement, the tracker rod being made in sections slidably engaged with each other for longitudinal adjustment, and means for longitudinally shifting the tracker rod.

6. In a tracker mechanism for player pianos, a supporting frame, oppositely disposed aligned music roll supporting spindles rotatably mounted in the frame and having longitudinal movement therein, a tracker rod extending across the top of the frame and slidably supported thereon and having downwardly extending ends having rotative engagement with the spindles, the spindles and tracker rod having unitary longitudinal movement, said tracker rod being formed in three sections engaged with each other for relative longitudinal movement and adjustment, pneumatics mounted above the tracker rod and engaged with the middle section thereof and means for longitudinally shifting the tracker rod.

In testimony whereof I hereunto affix my signature in the presence of two witnesses.
